CONTROL SYSTEM FOR ELECTRIC FURNACES.

1,349,363.

Specification of Letters Patent.

Patented Aug. 10, 1920.

Application filed February 15, 1919. Serial No. 277,308.

To all whom it may concern:

Be it known that I, ORA A. COLBY, a citizen of the United States, and a resident of Larimer, in the county of Westmoreland 5 and State of Pennsylvania, have invented a new and useful Improvement in Control Systems for Electric Furnaces, of which the following is a specification.

My invention relates to electric furnaces, 10 and particularly to methods of control for electric-resistance furnaces.

One object of my invention is to provide an automatic control system for electric-resistance furnaces where the resistor has a 15 negative temperature-resistance coefficient.

Another object of my invention is to provide an automatic control system for electric-resistance furnaces that will be simple, 20 relatively inexpensive, durable and easily kept in working order.

Another object of my invention is to provide a control system that will enable the operator to maintain any desired temperature in the furnace within a relatively small 25 range of temperature, and that will enable him to easily change the working temperature in the furnace to any other desired value.

In operating electric-resistance furnaces 30 that have a negative-temperature-resistance coefficient, it is necessary to apply a voltage to the cold resistor that is much higher than is required when the resistor has been heated to its working temperature. Where a transformer is used to reduce the voltage to the 35 value required by the furnace, this variable voltage may be obtained by changing the number of effective turns in the primary winding of the transformer, and my invention 40 relates to the method of accomplishing this object.

In practising my invention, I provide a plurality of electromagnetically operated switches to control the connection of the 45 electric supply circuit to the primary winding, actuating these switches either by circuit-closing relays that are controlled by thermostats or by the thermostats themselves. The thermostats are caused to operate by a plurality of heating coils of different heating capacities that are connected to the secondary winding of a suitable current transformer which is energized by the current flowing through the resistor of the

furnace. A rheostat is provided in shunt to 55 the heating coils, so as to be able to adjust the current value in the furnace at which the control apparatus will operate. The thermostats are electrically interlocked and the electromagnetically operated switches 60 may be interlocked, mechanically or otherwise, so as to preclude more than one switch being closed at one time and thereby short circuiting a section of the transformer.

Figure 1 of the drawing is a diagram of 65 apparatus and circuits embodying circuit-closing relays to actuate the electromagnetic switches, the relays being controlled by thermostats. Fig. 2 is a diagram of apparatus and circuits embodying double-contact 70 thermostats for controlling the electromagnetic switches.

Referring to Fig. 1, an electric supply circuit 10 energizes a transformer A through a switch 11, the current flowing through the 75 conductor 12 to the primary winding of the transformer A at either the point 20 or the point 21 (according to the position of the switch member 19), then through the active portion of the winding and out through one 80 of the conductors 13, 14 and 15. The conductors 13, 14 and 15 are connected to the other conductor 12^a of the supply circuit 10 through electromagnetic switches 16, 17 and 18, respectively. The single-pole, double- 85 throw switch member 19 may be manually thrown to engage either the contact terminal 20 or the contact terminal 21, according to the number of turns of the primary winding to be included in the circuit. The sec- 90 ondary winding of the transformer A is di- vided into two halves that may be connected in series or in parallel by a switch 22 and delivers current to the furnace B through the conductors 25 and 24 and the protective 95 circuit-breaker 23.

A plurality of circuit-closing relays 26, 27, and 28, close and open the circuits through the coils of the respective electro- 100 magnetic switches 16, 17, and 18. One of the terminals of each of the coils of switches 16, 17 and 18, is connected to the conductor 12^a by means of the conductor 29, while the other terminals of the coils are connected to corresponding stationary contact 105 members of the relays 26, 27 and 28, respectively. The other corresponding contact members of the relays 26, 27 and 28, are

connected to a conductor 33 that is connected to the conductor 12. One terminal of the operating coil of relay 26 is connected to the conductor 33, and its other terminal 5 is connected to the contact terminal 35 of a thermostat 36. The fixed end of a bimetallic strip 36^a is connected to the conductor 12^a through a conductor 37. One terminal of the coil of relay 27 is connected 10 to the conductor 33, while the other terminal of the coil is connected to the contact terminal 39 of a thermostat 40 through a conductor 38. The fixed end of a bi-metallic strip 40^a is connected to the fixed end of a like strip 42^a of a thermostat 42 by means 15 of a conductor 41. A contact terminal 43 is connected to the conductor 12^a of the supply circuit by means of a conductor 44. One terminal of the coil of relay 28 is connected 20 to the conductor 33, while the other terminal of the coil is connected to a contact terminal 45 by means of a conductor 46. The fixed end of the strip 47^a of a thermostat 47 is connected, by means of a conductor 48, 25 to the fixed end of the strip 49^a of a thermostat 49. The contact terminal 50 of a thermostat 49 is connected, by means of conductor 44, to conductor 12^a of the supply circuit. The bi-metallic strips 36^a, 42^a and 30 49^a engage the respective contact terminals 35, 43 and 50 when there is no current flowing through the heating coils of the thermostats, while the strips 40^a and 47^a of the thermostats 40 and 47 are out of engagement 35 with the contact terminals 39 and 45, under like conditions.

Heating coils 36^b, 40^b, 42^b, 47^b and 49^b are mounted in the casings of the respective thermostats 36, 40, 42, 47 and 49 and are 40 connected, in series, across the secondary winding 51 of a current transformer 51^a that is connected to the conductor 24 leading to one contact terminal of the furnace B. The heating coils may be connected to the 45 conductor 24 in any other suitable manner, if desired. A rheostat 52 is connected in parallel with the heating coils and serves as a means for regulating the amount of current flowing through them. The heating 50 coils 36^b, 40^b, 42^b, 47^b and 49^b are so designed that the coil 36^b has, relatively, the largest amount of energy loss, 40^b the next largest, and so on down to 49^b, which has relatively the smallest energy loss of the 55 group of heating coils.

Fig. 2 shows two double-contact thermostats and one single-contact thermostat to control the operation of the electromagnetic switches 16, 17 and 18. One terminal of the 60 coil of switch 16 is connected to the supply conductor 12^a by means of conductor 29, and the other terminal is connected to the contact terminal 65 of a thermostat 60 by means of a conductor 64. One terminal of 65 each of the coils of the switches 17 and 18

is connected to the same conductor 29, and the other terminal of the coil of switch 17 is connected to a contact terminal 68 of the thermostat 60 by means of a conductor 66, while the other terminal of the coil of switch 18 is connected to the contact terminal 73 of a thermostat 63 by means of a conductor 67. The fixed end of a bimetallic strip 60^a is connected to a contact terminal 70 by means of a conductor 69. 75 The fixed end of a strip 62^a is connected to the conductor 12 of the supply circuit 10. A contact terminal 72 is connected to the fixed end of a strip 63^a by means of a conductor 74. The free ends of the bi-metallic strips 60^a, 62^a and 63^a engage, respectively, the contact terminals 65, 70 and 73 when the thermostats are cold. The heating coils 60^b, 62^b and 63^b are connected in series and across the terminals of the winding 51 of the current transformer 51^a. The heating coils are so designed that coil 60^b has relatively the largest watt loss, the coils 62^b and 63^b having each a relatively, and progressively, smaller energy loss. 90

If the position of the various parts is as shown in Fig. 1 and it is desired to place the system in operation, the procedure is as follows: Throw the switch 22 to the left to connect the two halves of the secondary 95 winding of the transformer A in parallel, and throw the switch member 19 to engage the contact terminal 20. Then close the switch 11 in the supply circuit 10. Current will flow through a control circuit, comprising the following: from conductor 12^a through conductor 37, thermostat strip 36^a, contact terminal 35, conductor 34, the coil of relay 26 and conductor 33, to conductor 12. This will cause relay 26 to close a circuit as follows: from conductor 29 through the coil of switch 16, conductor 30, contact terminals and contact bridging member of relay 26 to conductor 33, and thence to the other conductor 12 of the supply circuit 10. 105 This will operate to close a circuit as follows: from the conductor 12^a, through the contact terminals and contact bridging member of the switch 16, conductor 13, a portion of the primary winding of the transformer A, conductor 20 and switch member 19 to conductor 12. As the number of turns of the primary winding included in the circuit is relatively small, a relatively high secondary voltage will be applied to the 110 terminals of the resistors of furnace B, and a current will flow through the furnace, resulting in a gradual increase of temperature of the resistor. As the temperature rises, the resistance will decrease, resulting in an 115 increase of current and, therefore, a further rise of temperature. A current is induced in the secondary winding 51 of the current transformer 51^a that is proportional to the 120 current flowing through the resistor of the 125 furnace B. The current in the secondary winding 51 of the current transformer 51^a will cause the switch 16 to open, and the current in the primary winding of the transformer A will decrease, resulting in a further 130

- furnace B. This current flows through a circuit comprising a conductor 53, the heating coils 36^b, 40^b, 42^b, 47^b and 49^b, connected in series, and a conductor 54, and, if the 5 rheostat 52 is in circuit, a proportional part of this current will flow through it. As the heating coil 36^b has relatively the maximum watts loss, the strip 36^a will be caused to operate first. At a predetermined value of 10 current in furnace B, the derived current in the transformer 51^a and its circuit, as described above, will be such as to cause the strip 36^a to be disengaged from its contact terminal 35 and thereby open the circuit 15 through the coil of relay 26. This, in turn, will open the control circuit through the switch 16 and thereby disconnect the conductor 12^a from the conductor 13 and from the primary winding of the transformer A. 20 The adjustment of the thermostat 40 and the watts loss in the heating coil 40^b are such that the strip 40^a will engage the contact terminal 39 as soon as the strip 36^a is disengaged from its contact terminal 35. A new 25 control circuit will then be established comprising the conductor 44, contact terminal 43, strip 42^a, conductor 41, strip 40^a, contact terminal 39, conductor 38, the coil of relay 27, and conductor 33 to conductor 12. This will 30 operate to close a circuit through relay 27 as follows: from conductor 12^a through conductor 29, the coil of switch 17, conductor 31, contact terminals and contact bridging member of relay 27 and conductor 33 to conductor 12. This will cause the switch 17 to 35 close and establish the following circuit; from conductor 12^a, through the contact terminals and contact bridging member of switch 17, conductor 14, the portion of the 40 primary winding of transformer A, between conductor 14 and terminal 20, and switch member 19, to conductor 12. This circuit, therefore, comprises a larger number of turns of wire of the primary winding, and hence, 45 the secondary voltage of the transformer will be reduced, with a corresponding reduction in the current flowing through the resistor of furnace B.
- If the resistance of the furnace continues 50 to decrease, the current flowing through the furnace and through the conductor 24 will continue to increase and, therefore, the current in the winding 51 will increase until the heat generated in the heating coil 42^b will 55 cause the strip 42^a to be disengaged from the contact terminal 43. This will open the circuit through the coil of relay 27 and this, in turn, will cause switch 17 to open and de- 60 energize the transformer A.
- The adjustment of thermostat 47 is such 65 that the strip 47^a will engage the contact terminal 45, immediately after strip 42^a is disengaged from contact terminal 43, and close a circuit through the coil of relay 28, similar 70 to that described for the other relays. This 75 will energize switch 18 and connect the conductor 12^a to conductor 15 and, consequently, a still larger number of turns of the primary winding will be included in the circuit. The secondary voltage will, therefore, be again 80 reduced and, within normal limits, should be low enough to permit only such value of current to flow in the furnace B, as will maintain the desired temperature therein. If, however, the resistance of furnace B de- 85 creases still further, with a corresponding increase of current, the strip 49^a will be disengaged from its contact terminal 50 and will open the circuit through the coil of relay 28. This will cause the switch 18 to open and disconnect the conductor 12^a from the transformer, and, therefore, no current will flow 90 through the furnace. In a relatively short time, the strip 49^a will become cool enough to again engage the contact terminal 50, thus 95 restoring the circuit through the coil of relay 20^a, resulting in switch 18 closing, and reenergizing the transformer, with the largest number of turns of the primary winding included in the circuit. 100
- Should it be desired to operate the furnace at a higher temperature, the rheostat 52 may be connected in circuit and the less the resistance connected across the conductors 53 and 54, the greater will be the current diverted from the heating coils of the thermostats. The current through the furnace B must, therefore, be greater to cause the thermostats to operate as described above and, hence, the temperature of the furnace 105 will be higher. The circuit-breaker 23 is provided as a final safety device, to protect the resistor of furnace B in case of accident, and is not a part of my invention. 110
- When it is desired to omit the circuit-closing relays, the system shown in Fig. 2 may be used and the thermostats will operate to close and open the circuits through the coils of the electromagnetic switches themselves. Assume that switch 22 has been 115 closed, that switch 19 engages the contact terminal 20 and that switch 11 is then closed. A control circuit will be established as follows: from conductor 12, through conductor 71, the strip 62^a, contact terminal 70, conductor 69, strip 60^a, contact terminal 65, conductor 64, the coil of switch 16, and conductor 29, to conductor 12^a. This will cause 120 the switch 16 to close and energize the transformer A, through the following circuit: from conductor 12^a, through the contact terminals and contact bridging member of switch 16, conductor 13, a portion of the primary winding of transformer A, terminal 20, and switch member 19, to conductor 12. This will cause a relatively high 125 secondary voltage to be impressed on the resistor of furnace B and cause it to heat up. As the resistance decreases and the current increases, the derived current in the cur- 130

rent transformer 51^a will also increase and the thermostat heating coils will heat up. As coil 60^b has the relatively largest watt loss, it will cause the strip 60^a to be disengaged from contact terminal 65 and to immediately engage contact terminal 68. This action opens the control circuit of switch 16, causing the conductor 12^a to be disconnected from the primary winding of the transformer and closes the control circuit of switch 17, causing it to close and connect conductor 12^a to conductor 14, and, therefore, to the primary winding of the transformer A, with a relatively larger number of turns included in the circuit. This will reduce the voltage impressed on the resistor of the furnace and, hence, tend to reduce the current or to maintain it at a constant value. If the resistance of the furnace B decreases further, with a corresponding increase of current, the heating coil 62^b will cause the strip 62^a to be disengaged from contact terminal 70 and to engage contact terminal 72. This action will open the circuit through the coil of switch 17 and close the circuit through the coil of switch 18, comprising the following: from conductor 12, conductor 71, strip 62^a, contact terminal 72, conductor 74, strip 63^a, contact terminal 73, conductor 67, the coil of switch 18 and conductor 29, to conductor 12^a. This will cause the switch 18 to close and connect the conductor 12^a to the primary winding of the transformer A through conductor 15 and, therefore, a still larger number of turns is included in the circuit. This will reduce the voltage impressed on the furnace B and, therefore, will tend to reduce the current flowing through the resistor or to keep it at a constant value, even if the resistance of the furnace decreases. If the resistance should decrease still more, the derived current flowing through the winding 51 and the heating coils of the thermostats will cause the strip 63^a to be disengaged from contact terminal 73. This will open the circuit through the coil of switch 18, causing this switch to open and interrupt the circuit through conductor 15 and, therefore, deenergizing the transformer A. As no current is flowing in the furnace and thermostat heating coils, the bi-metallic strip 63^a will immediately begin to cool and will soon reengage the contact terminal 73, restoring the circuit through the coil of switch 18, causing that switch to close and reenergize the transformer. The amount of current in the furnace B, and, hence, the operating temperature may be adjusted by means of rheostat 52, as described in connection with Fig. 1.

If a higher secondary voltage is desired at any time, switch member 19 may be so thrown as to engage the contact terminal 21 and thus cut out a part of the primary

winding of the transformer A. If a still higher secondary voltage is required, switch 22 may be so thrown as to connect the two halves of the secondary winding of transformer A in series. These two switches are provided mainly to allow of securing a relatively large range of voltage adjustment to meet all conditions that may arise in the operation of such furnaces and are not parts of my invention.

While I have shown specific applications of my system, I desire that only such limitations shall be placed thereon as are imposed by the prior art or are specifically set forth in the appended claims:

I claim as my invention:

1. An electrical heating system comprising a main heating element the temperature of which is to be regulated, an auxiliary heating element out of thermal communication with the main heating element and receiving current in proportion to that supplied to the main heating element, means for adjusting the ratio of the currents in the two heating elements, and means actuated in response to variations of the temperature of the auxiliary heating element for regulating the temperature of the main heating element.

2. An electrical heating system comprising a main heating element having a negative-temperature-resistance coefficient, the temperature of which is to be regulated, an auxiliary heating element out of thermal communication with the main heating element and receiving current in proportion to that supplied to the main heating element, and means actuated in response to variations of the temperature of the auxiliary heating element for regulating the temperature of the main heating element.

3. An electrical heating system comprising a main heating element having a negative-temperature-resistance coefficient, the temperature of which is to be regulated, an electrical circuit supplying the same, an auxiliary heating element, means for supplying to the auxiliary heating element a current derived from the circuit supplying the main heating element that is in direct proportion to the current in said circuit, and means actuated in response to variations of the temperature of the auxiliary heating element for regulating the temperature of the main heating element.

4. An electrical heating system comprising a main heating element having a negative-temperature-resistance coefficient the temperature of which is to be regulated, a transformer having a plurality of taps connected to the primary winding, an electrical circuit for energizing said transformer, electromagnetic switches for rendering effective predetermined portions of the winding of said transformer, means for controlling said electromagnetic switches, and an auxiliary

heating element out of thermal communication with the main heating element for actuating said control means.

5. An electrical heating system comprising

- 6 a main heating element having a negative-temperature-resistance coefficient the temperature of which is to be regulated, a transformer, an electrical circuit supplying said transformer, electromagnetic switches
10 for energizing predetermined portions of the primary winding of said transformer, temperature-actuated means for controlling said electromagnetic switches, an auxiliary heating element out of thermal communication
15 with the main heating element for controlling said temperature-actuated control means, and means for supplying to the auxiliary heating element a current derived from the circuit supplying the main heating
20 element.

6. An electrical heating system comprising a main heating element having a negative-temperature-resistance coefficient, the temperature of which is to be regulated, a

- 25 transformer, an electrical circuit for energizing said transformer, circuit-closing devices for energizing predetermined portions of the primary winding of said transformer, temperature-actuated means for controlling
30 said circuit-closing devices, an auxiliary heating element out of thermal communication with the main heating element for controlling said temperature-actuated control means, and means for supplying to the auxiliary heating element a current derived from the circuit supplying the main heating element that is in direct proportion to the current in said circuit.

7. An electrical heating system comprising

- 40 a main heating element having a negative-temperature-resistance coefficient, the temperature of which is to be regulated, a transformer, an electrical circuit for supplying energy to said transformer, circuit-closing devices for energizing predetermined portions of the primary winding of said transformer, means for controlling said circuit-closing devices, said means being responsive to variations of current in the main heating element.

8. An electrical heating system comprising a main heating element having a negative-temperature-resistance coefficient, the temperature of which is to be regulated, a

- 55 transformer having a plurality of taps on the primary winding, an electrical circuit for energizing said transformer, a plurality of circuit-closing devices for rendering effective predetermined portions of the primary winding of said transformer, a plurality of temperature-actuated means for controlling said circuit-closing devices, said temperature-actuated control means being arranged to preclude more than one circuit-closing device being closed at one time.

9. An electrical heating system comprising an electrical supply circuit, a transformer having a plurality of taps on the primary winding, a main heating element having a negative-temperature-resistance coefficient, the temperature of which is to be regulated, a plurality of circuit-closing devices for energizing portions of the winding of said transformer, means for causing said circuit-closing devices to operate in predetermined order, an auxiliary heating element out of thermal communication with the main heating element for actuating said means, and means for supplying to the auxiliary heating element a current derived from the circuit supplying the main heating element.

10. In an electrical heating system the combination with a transformer having a plurality of sections in the primary winding, 85

an electrical circuit supplying said transformer, a main heating element having a negative-temperature-resistance coefficient, the temperature of which is to be regulated and receiving its current from the secondary 90 of said transformer, circuit-closing devices for energizing predetermined portions of the primary winding of said transformer, temperature-actuated means for controlling said circuit-closing devices, and an auxiliary 95 heating element, out of thermal communication with the main heating element, for controlling said temperature-actuated means, of means for supplying to the auxiliary heating element a current derived from the 100 circuit supplying the main heating element that is in proportion to the current in said heating element, and means for adjusting the proportion of the currents in the two heating elements.

11. An electrical heating system comprising

105 a transformer having a plurality of sections in the primary winding, an electrical circuit supplying energy to said transformer, a main heating element, having a negative-temperature-resistance coefficient, the temperature of which is to be regulated, a plurality of circuit-closing devices for energizing portions of said transformer, a plurality of temperature-actuated means for 110 controlling said circuit-closing devices, an auxiliary heating element, out of thermal communication with the main heating element, having a plurality of sections of different heating capacities adapted to actuate 115 said circuit-closing devices in predetermined order, means for supplying to the auxiliary heating element a current derived from the circuit supplying the main heating element that is in direct proportion to the current in 120 said circuit, and means for adjusting the proportion of the currents in the two heating elements.

12. An electrical heating system comprising a main heating element, having a nega- 130

tive-temperature-resistance coefficient, the temperature of which is to be regulated, an electrical circuit supplying said main heating element, an auxiliary heating element, 5 having a plurality of sections of different heating capacities, out of thermal communication with the main heating element and receiving current in proportion to that supplied to the main heating element, and means 10 actuated in response to variations of the auxiliary heating element for regulating the temperature of the main heating element.

13. An electrical heating system comprising a main heating element, having a negative-temperature-resistance coefficient, the temperature of which is to be regulated, an auxiliary heating element having a plurality of sections of different heating capacities, out 20 of thermal communication with the main heating element and receiving current in proportion to that supplied to the main heating element, means for adjusting the ratio of the currents in the two heating elements, 25 and means actuated in response to variations of the temperature of the auxiliary heating element for regulating the temperature of the main heating element.

14. An electrical heating system comprising a main heating element having a negative-temperature-resistance coefficient, the temperature of which is to be regulated, a transformer having a plurality of sections in the primary winding, an electrical circuit 35 supplying the same, an auxiliary heating element out of thermal communication with the main heating element and receiving current in proportion to that supplied to the main heating element, means actuated in response to increases of the temperature of the auxiliary heating element for increasing the effective number of turns of the primary winding connected to the electrical circuit.

15. An electrical heating system comprising a main heating element having a negative-temperature-resistance coefficient, the temperature of which is to be regulated, a transformer having a plurality of taps on the primary winding, an electrical circuit 45 supplying the same, an auxiliary heating element out of thermal communication with the main heating element and receiving current in proportion to that supplied to the main heating element, and means actuated in response to increases of the temperature of the auxiliary heating element for increasing the effective number of turns of the primary winding connected to the electrical circuit and for finally disconnecting the supply circuit from said transformer winding upon the occurrence of a predetermined temperature.

16. An electrical heating system comprising a main heating element having a negative-temperature-resistance coefficient, the

temperature of which is to be regulated, a transformer having a plurality of sections in the primary winding, an electrical circuit supplying said transformer, an auxiliary heating element having a plurality of sections of different heating capacities out of thermal communication with the main heating element and receiving current in proportion to that supplied to the main heating element, electromagnetic switches for energizing portions of the primary winding of said transformer, and a plurality of double-contact thermostats controlled by said auxiliary heating element, for actuating said electromagnetic switches in predetermined order to maintain a practically constant current in the main heating element.

17. An electrical heating system comprising a main heating element having a negative-temperature-resistance coefficient, the temperature of which is to be regulated, a transformer having a plurality of taps on the primary winding, an electrical circuit supplying the same, an auxiliary heating element out of thermal communication with the main heating element and receiving current in proportion to that supplied to the main heating element, and means actuated in response to increases of the temperature of the auxiliary heating element for increasing the effective number of turns of the primary winding connected to the electrical supply circuit and for finally disconnecting the supply circuit from said transformer winding upon the occurrence of a predetermined temperature—and for reconnecting said supply circuit to said transformer when the temperature drops to a value lower than said predetermined value.

18. An electrical heating system, comprising a main heating element having a negative-temperature-resistance coefficient, the temperature of which is to be regulated, a transformer having a plurality of sections in the primary winding, an electrical circuit supplying said transformer, an auxiliary heating element, having a plurality of sections of different heating capacities, out of thermal communication with the main heating element and receiving current in proportion to that supplied to the main heating element, electromagnetic switches for energizing sections of said transformer, circuit-closing relays for controlling said electromagnetic switches, and a plurality of thermostats controlled by said auxiliary heating element for actuating said circuit-closing relays to cause said electromagnetic switches to close and to open in predetermined order to maintain a practically constant current in said main heating element.

In testimony whereof, I have hereunto subscribed my name this 31st day of Jan., 1919.

ORA A. COLBY,
